UNITED STATES PATENT OFFICE.

CHARLES E. HARTHAN, OF LYNN, MASSACHUSETTS, ASSIGNOR TO GENERAL ELECTRIC COMPANY, A CORPORATION OF NEW YORK.

STARTING-RHEOSTAT.

SPECIFICATION forming part of Letters Patent No. 729,762, dated June 2, 1903.

Application filed March 8, 1902. Serial No. 97,322. (No model.)

To all whom it may concern:

Be it known that I, CHARLES E. HARTHAN, a citizen of the United States, residing at Lynn, county of Essex, State of Massachusetts, have 5 invented certain new and useful Improvements in Starting-Rheostats, of which the following is a specification.

This invention relates to switches for controlling the circuits of electric motors and 10 other electrodynamic apparatus, such as starting-rheostats, circuit-breakers, and the like; and its object is to provide means for automatically opening the circuit on an overload. The usual apparatus for accomplishing 15 this result includes an electromagnet adjusted to actuate its armature when the current becomes excessive, and thus short-circuit the electromagnet which retains the arm of the starting-rheostat or the main contact of 20 the circuit-breaker in the "on" position, thereby permitting a spring to return said arm or contact to the "off" position. The overload electromagnet acts the instant the predetermined excess of current occurs, which 25 under some circumstances is objectionable, since a momentary flow of excessive current is often not injurious—such, for instance, as happens when starting a motor or throwing on heavy loads.

30 My invention provides an overload device which does not operate instantly, but only after an interval of a minute or two.

It consists of a thermostat in series with the line, so that it will be heated by the current. 35 With an excessive flow the thermostat becomes sufficiently hot to close a pair of contacts, and thereby short-circuit the retaining-magnet and permit the spring to throw off the rheostat or circuit-breaker, and thereby 40 open the circuit. This operation occupies between one and two minutes; but when the current is cut off the thermostat quickly cools and opens the short-circuiting contacts.

The device can be made to operate at any 45 desirable range of current or degree of overload.

In the accompanying drawings, Figure 1 is a front elevation of a starting-rheostat embodying my invention. Fig. 2 is a top plan 50 view of the thermostat on a larger scale. Fig. 3 is an end view of the same. Fig. 4 is a dia-

gram of the circuits, and Fig. 5 shows the invention applied to a circuit-breaker.

Referring to Figs. 1, 2, 3, and 4, at A is shown the armature and at B the field-coil of 55 a shunt-wound motor, whose circuit 1 1 is opened and closed by a double-pole switch C and controlled by a rheostat D. The arm d of the rheostat makes contact with the steps d', thereby successively cutting out the resistance-coils d² from the armature-circuit 2 2. An electromagnet d³ in the field-coil circuit 3 3 retains the arm in position when all the resistance has been cut out. When a shunt-circuit 4 4 is closed around this magnet, a spring 60 d⁴ returns the arm d to the off position, as shown in Figs. 1 and 4, opening the armature-circuit, and so stopping the motor. These parts are all old and in common use. My invention lies in the device which I employ in 65 70 this combination for closing the shunt 4 4 and short-circuiting the retaining-magnet d³.

In the shunt is included a pair of contacts, normally separated so as to keep the shunt open. Instead of a magnet for closing these 75 contacts I provide a thermostatic circuit-closer so arranged that its temperature will vary with the current. At a predetermined degree of heat the thermostat closes the contacts. 80

Various forms of thermostats may be employed in this connection. I prefer the one shown in the drawings, consisting of two arms E, each composed of two metals having dissimilar coefficients of expansion and contraction. These arms I put in series with the armature, attaching them at one end to stationary clips E' and connecting them electrically by a leaf-spring E². At their free ends they carry the contacts F, one or both 90 of which may be adjustable. These contacts are insulated from the arms, preferably by being mounted in laterally-projecting fingers G, secured to the arms by screws g, but insulated therefrom by interposed insulation H. 95

In case of an overload the arms on becoming heated close the contacts F and shunt the magnet d³, thereby allowing the spring d⁴ to open-circuit the armature of the motor.

Fig. 5 shows a circuit-breaker equipped 100 with my invention and in circuit with a generator and a trolley-car. The fixed contacts

I, the movable bridging-contact K, the blow-out coils L, the toggle M, with its handle M', and the circuit-opening spring N are all of any usual construction. In place of the customary overload-magnet I employ a magnet P, which holds the toggle locked so long as current flows through it. My thermostatic overload device is arranged so that an excessive flow of current will heat the thermostat 10 to a point where it will close the shunt, thereby de-energizing the magnet P and tripping the circuit-breaker.

My invention is not necessarily limited to the exact construction shown in the drawings, 15 but may be varied in many ways without departing from the spirit or scope thereof.

What I claim as new, and desire to secure by Letters Patent of the United States, is—

1. The combination with a switch having 20 a retaining-magnet, of a thermostat whose temperature varies with the current, and a shunt around said magnet controlled by said thermostat.

2. The combination with a switch having 25 a retaining-magnet, of a thermostat in series

with the switch, and a shunt around said magnet controlled by said thermostat.

3. The combination with a switch having a retaining-magnet, of a thermostatic arm in series with the switch, a contact on said arm, and a shunt around said magnet including 30 said contact.

4. The combination with a switch having a retaining-magnet, of two connected thermostatic arms in series with the switch, and insulated contacts carried by said arms and included in a shunt around said magnet. 35

5. The combination with a switch having a retaining-magnet, of two thermostatic arms fastened at one end, a leaf-spring connecting 40 said arms, an insulated finger at the free end of each arm, and a contact carried by said finger and included in a shunt around said magnet.

In witness whereof I have hereunto set my 45 hand this 6th day of March, 1902.

CHARLES E. HARTHAN.
